UNITED STATES PATENT OFFICE.

WILLIAM BAXTER, JR., OF BALTIMORE, MARYLAND, ASSIGNOR TO THE BAXTER ELECTRIC MANUFACTURING AND MOTOR COMPANY, OF SAME PLACE.

DESIGN FOR AN ELECTRIC-MOTOR FRAME.

SPECIFICATION forming part of Design No. 17,256, dated April 12, 1887.

Application filed October 27, 1886. Serial No. 217,381. Term of patent 14 years.

To all whom it may concern:

Be it known that I, WILLIAM BAXTER, Jr., a citizen of the United States, residing at Baltimore, Maryland, have invented a certain 5 new and original Design for an Electric-Motor Frame, fully described and represented in the following specification and the accompanying drawings, forming a part of the same.

Figure 1 is an end elevation, and Fig. 2 a 10 side elevation, of my newly-designed electric-motor frame, the drawings also showing the other parts of the motor, which are not claimed herein, as I have made them a subject of a separate patent application, No. 217,306, filed Oc- 15 tober 27, 1886.

As shown in Fig. 1, the frame is of arch 20 form at its middle, *a*, with a concavity, *b*, underneath, and a curved top, *a'*, nearly concentric with such concavity. At each side of the arch the frame is formed symmetrically, 25 extending upwardly and outwardly, forming curved ends *c*. The letter *c* is applied in Fig. 1 to the side and in Fig. 2 to the top of the upwardly - curved end. Members *d* extend from the ends *c*, being inclined upwardly and 30 inwardly, and passing into heads *e*, which are concaved upon their adjacent faces. Arms *i* project laterally at each side from the middle of the arch, as shown in Fig. 2; but they 35 are not a material part of my design, the essential features of which are the arch *a*, curved

upwardly in the middle, and the ends curved outwardly and upwardly, as shown.

This design forms a very simple, elegant, and cheap frame for an electric motor. 35

I hereby disclaim my co-pending patent application, No. 217,306, filed October 27, 1886.

Having described my design, what I claim herein is—

1. The design for an electric motor frame 40 herein shown and described, and consisting in the frame having arch *a*, curved upwardly at the middle, with the concavity *b* underneath, and the symmetrical ends *c*, curved upwardly and outwardly, substantially as herein set 45 forth.

2. The design for an electric-motor frame, 50 having the arch *a*, curved upwardly at the middle, with a concavity, *b*, underneath, the symmetrical ends *c*, curved outwardly and upwardly, as described, the members *d*, inclined upwardly and inwardly from the ends *c*, and passing into heads *e*, concaved upon their adjacent faces, substantially as herein shown and described. 55

In testimony whereof I have hereunto set my hand in the presence of two subscribing witnesses.

WM. BAXTER, JR.
